UNITED STATES PATENT OFFICE.

HARRY DINHOFER, OF NEW YORK, N. Y.

DESIGN FOR A FINGER RING.

Application filed May 28, 1924. Serial No. 9,724. Term of patent 7 years.

To all whom it may concern:

Be it known that I, HARRY DINHOFER, a citizen of the United States, residing at the city, county, and State of New York, have invented a new, original, and ornamental Design for Finger Rings, of which the following is a specification, reference being had to the accompanying drawing, forming a part hereof, in which the figure shown is a perspective view of a finger ring, showing my new design.

I claim:

The ornamental design for a finger ring, as shown.

HARRY DINHOFER.
